UNITED STATES PATENT OFFICE

169,426

HAND MICROPHONE

John Frederick Dewsall, Enfield, England, assignor to Cosmocord Limited, Enfield, England, a British company

Application December 27, 1951, Serial No. 17,837
In Great Britain November 26, 1951

Term of patent 14 years

(Cl. D26—14)

To all whom it may concern:

Be it known that I, John Frederick Dewsall, a British subject, of Enfield, Middlesex, England, have invented a new, original, and ornamental Design for a Hand Microphone, of which the following is a specification, reference being had to the accompanying drawings, forming a part hereof.

Figure 1 is a side elevation view of a hand microphone, showing my new design;
Figure 2 is a front elevation thereof;
Figure 3 is a plan view thereof;
Figure 4 is an inverted plan view thereof;
Figure 5 is a rear view thereof; and

Figure 6 is a perspective view thereof.

I claim:

The ornamental design for a hand microphone, as shown.

JOHN FREDERICK DEWSALL.
